US0D1009394S

(12) **United States Design Patent** (10) **Patent No.:** **US D1,009,394 S**
(45) **Date of Patent:** **** Dec. 26, 2023**

(54) **FLOOR MOP**

(71) Applicant: **Carl Freudenberg KG**, Weinheim (DE)

(72) Inventors: **Willem Lijmbach**, Schriesheim (DE); **Johanna Koenigsberger**, Hamburg (DE); **Paul Fally**, Hamburg (DE); **Matthias Hecker**, Hamburg (DE)

(73) Assignee: **CARL FREUDENBERG KG**, Weinheim (DE)

(**) Term: **15 Years**

(21) Appl. No.: **29/802,802**

(22) Filed: **Aug. 9, 2021**

(30) **Foreign Application Priority Data**

Feb. 10, 2021 (EM) 008430623

(51) **LOC (14) Cl.** **07-05**

(52) **U.S. Cl.**

USPC **D32/50**

(58) **Field of Classification Search**

USPC D32/15, 19, 20, 52, 40, 41, 42, 43, 44, D32/45, 50, 51, 53

CPC A47L 13/20; A47L 13/225; A47L 13/58; A47L 13/128

See application file for complete search history.

(57) **CLAIM**

The ornamental design for a floor mop, as shown and described.

DESCRIPTION

FIG. 1 is a front-left perspective view of a floor mop showing our new design;

FIG. 2 is a left-side view thereof;

FIG. 3 is a right-side view thereof;

FIG. 4 is a front view thereof;

FIG. 5 is a back view thereof;

FIG. 6 is a top view thereof; and,

FIG. 7 is a bottom perspective view thereof.

The broken lines in the drawings illustrate portions of the floor mop which form no part of the claimed design.

1 Claim, 7 Drawing Sheets
